UNITED STATES PATENT OFFICE.

STEPHEN F. MOORE, OF MILWAUKEE, WISCONSIN.

CARVING-MACHINE.

SPECIFICATION forming part of Letters Patent No. 394,710, dated December 18, 1888.

Application filed June 18, 1888. Serial No. 277,405. (No model.)

To all whom it may concern:

Be it known that I, STEPHEN F. MOORE, of Milwaukee, in the county of Milwaukee and State of Wisconsin, have invented new and 5 useful Improvements in Carving-Machines; and I do hereby declare the following to be a full, clear, and exact description of said invention, reference being had to the accompanying drawings, and to the letters or figures of reference marked thereon, which form a part of 10 this specification.

My invention, to be hereinafter claimed, relates to improvements in the carving-machine for which I filed an application for Letters 15 Patent on January 7, 1888, which application is Serial No. 260,065, and inheres in the form and construction of the various parts of the mechanism and in the location, combination, and arrangement of those parts in the complete 20 device, substantially in the manner and for the purposes hereinafter described.

In the drawings, Figure 1 is a side elevation of my complete device in its improved form, having a modified material and pattern holding mechanism for operating on curved material. Fig. 2 is a plan from above of the tool-holding portion of my device, taken on line X X of Fig. 1. Fig. 3 is an elevation of a portion of the swinging arm and the thereto-pivoted standard and the band-wheel and pulley supported on the arm, partly in section to show form of construction. Fig. 4 is a plan of a portion of the upper or guide-carrying arm of the tool and guide carrying frame. Fig. 5 is the enlarged part of the upper inner 35 end of the swinging arm, showing its attachment and method of adjustment on its supporting-hinge. Fig. 6 is a central horizontal longitudinal section through the lower inner 40 end of the swinging arm and its supporting-hinge. Fig. 7 is an elevation of the counterpoise of the tool-carrying frame and of the standard in which its supporting-lever is pivoted. Fig. 8 is an inside elevation of the material and 45 pattern supporting frame. Fig. 9 is a vertical transverse section of the material and pattern supporting frame on line Y Y of Fig. 8. Fig. 10 is an elevation of the rear or inner side of one of the swinging tables shown in 50 Fig. 8.

The same letters and figures refer to like parts in all the views.

For conveniently supporting the tool-carrying mechanism a post or base piece, A, is

securely affixed to the side of the building B. 55 Brackets C and D are removably affixed to the post A, and a vertical shaft, 1, is supported and has its bearings in the brackets C and D. Shaft 1, at its lower end, has a conical bearing in the bracket C at E, and passes through 60 and has a bearing in another short arm of the same bracket at F, and has still another bearing in a journal-block, G, supported pivotally in the outer end of the bracket D. This arrangement of the bearings of the shaft 1 is 65 provided to secure a proper alignment and the least amount of friction with proper support. Near its upper extremity this shaft 1 carries a fixed driving-pulley, H, and a loose band-pulley, I, on which pulleys the driving-belt K 70 runs. A horizontally-swinging arm, 2, provided with hinges 3 and 4, to which it is adjustably secured, is by the hinge 3 pivoted on the bracket C above the shaft 1, and by the hinge 4 is pivoted in the bracket C below the 75 shaft 1, but in the line of the axis of the shaft 1.

The hinge 4 is provided with an enlarged vertical face having a recess, (seen in Fig. 6,) in which a pin or arbor, 5, integral with the 80 arm 2, enters and acts as a pivot about which a slightly oscillatory movement of the arm 2 may be had for the purpose of adjustment. The arm 2 is also provided with an enlarged end and face adapted to bear against the enlarged face of the hinge 4, through which enlarged part of the arm 2 are two curved slots, as shown in Fig. 5, which slots are adapted to receive the set-screws 6 6, which set-screws turn into the hinge 4, and are adapted to secure the arm firmly to the hinge, while providing for the adjustment of the arm 2 on the hinge 4. The hinge 3 is also provided with an enlarged part having a face adapted to receive thereagainst a corresponding face of an enlarged part of the arm 2, and this enlarged part of the arm 2 is provided with laterally-extending slots, through which pass the set-screws 7 7, which turn into the enlarged part of the hinge 3, as seen in Fig. 2, thereby 90 providing for the slight oscillatory or adjusting movement of the arm 2, also provided for in the connection made by the arm 2 with the hinge 4. This construction and connection of the arm 2 with its hinges 3 and 4 are 95 adapted to provide for a vertical alignment of the arm 2 or for a slight tilting of the arm, if desired, for the purpose of obtaining some 100 105

particular result with the cutting-tool. The hinge 4 has pointed or conical bearings in the lower part of the bracket C. To the outer bifurcate end of the arm 2 is pivoted or hinged a standard, 8.

To secure the least possible friction and a close adjustment of the parts, together with the greatest wearing strength, the standard 8 is pivoted onto arm 2 by means of steel-hardened pins, preferably constructed as shown in Fig. 3. A pin, 9, having an enlarged head is inserted vertically in an aperture therefor in the outer end of the lower bifurcate part of the arm 2, which pin 9 has a conical recess in its top adapted to receive and support the conical end of pin 10, which is inserted in an aperture therefor in the standard 8, and has a collar, 11, integral therewith, on which the standard 8 bears and is supported. The pin 12, having an enlarged top, is inserted in an aperture therefor in the upper part of the standard 8, and a pin, 13, is inserted in the upper bifurcate part of the arm 2, and terminates at its lower end in a conical point fitting into a corresponding recess in the pin 12. All these pins, 9, 10, 12, and 13, are secured adjustably in their respective bearings by set-screws 14 14 turning against them. A lower tool-carrying arm, 15, and an upper guide-carrying arm, 16, connected together by the rods 17 17, forming a tool and guide carrying frame, are supported and have a vertical movement on the standard 8.

The arm 15 is provided with two inwardly-projecting pins, 18 18, inserted movably in apertures therefor opposite to each other in the bifurcate end of the arm 15, which pins 18 18 are diamond-pointed and enter and fit into vertical grooves therefor in the standard 8, as shown in Fig. 2. The upper arm, 16, is provided with two sets of diamond-pointed steel pins, 19 19 and 19' 19', opposite each other in pairs in apertures therefor in the bifurcate end of the arm 16, which pins have their bearings in corresponding V-shaped vertical grooves in the standard 8. All these pins, 18 18, 19 19, and 19' 19', are provided with re-enforcing screws 20, for forcing them forward endwise to take up wear, and also with set-screws 21 21, to secure them firmly in position when adjusted by the screws 20 20. By means of this double set of ways and pins 19 19 19' 19' a correct and reliable vertical movement of the tool and guide carrying frame is secured with the minimum amount of friction. To limit the vertical movement of this frame two stops, 22 22, provided with vertical slots, are secured adjustably to the standard 8 by set-screws 23 23, passing through the slots and turning into the standard. This tool and guide carrying frame is supported and counterpoised by means of the oscillating lever 24, pivoted in the upper end of the upright 25, which upright is integral with standard 8, one arm of which lever 24 is connected to the tool and guide car-

rying frame by the thereto-pivoted rod 26, and on the other arm of which lever is the counterpoising-weight 27, adjustable on the 70 arm of lever 24. To reduce the friction to the minimum amount this lever 24 is pivoted on the upright arm 25 by means of diamond-pointed set-screws 28 28, as shown in Fig. 7. The lever 24, supported in upright 25 on 75 standard 8, and connected to the tool and guide carrying frame by rod 26, all have fixed positions relative to each other so far as a horizontal motion is concerned, so that the horizontal swinging of the arms 15 and 16 carries 80 with them the lever 24, and no change of position or twisting relative to each other occurs as would occur if the lever 24 were pivoted on some bracket fixed to the immovable post A or to the building. In the free outer 85 end of arm 16 an adjustable guide, 29, is carried, which is made adjustable in the arm 16 by means of an adjustable sleeve, 30, as fully described and claimed in my previous application hereinbefore referred to. The free outer 90 end of the arm 15 is expanded into a globe-like bracket, 31, and therein is supported and carried the spindle which carries the cutting-tool 32. A fixed band-wheel, 33, on shaft 1 carries a belt, 34, which runs on a band-wheel, 95 35, integral with the pulley 36, which carries the belt 37, running on a pulley on the tool-carrying spindle within the bracket 31.

A belt guiding and tightening pulley, 38, is supported on an arbor adjustable in a slot in 100 the arm 15. The band-wheel 35 and integral pulley 36 are supported and have their bearings on conical-pointed steel pins in the lower part of the bracket 2, the axis of which wheel and pulley is in a line with the axis of the 105 standard 8. The steel pins 13 and 63 are screw-threaded and turn into apertures therefor in the arm 2, and are each provided with jam-nuts 64 64 and 65 65 at their upper and lower ends, respectively, which are adapted to 110 be turned down on the pin against the supporting-arm, whereby the pin is locked in position and may be adjusted up or down.

In front of the tool and guide carrying mechanism, and so located as to support the material and pattern, respectively, within the arc made by the swinging arms 15 and 16, is the vertical moving and adjustable frame 39, supported on the frame-work 40 rigid to the post A. This bracket 40 is secured against any 115 lateral or swinging movement by the stay-rods 41 41, secured thereto and to the adjoining wall. The frame 39 is adjusted up and down by means of the hand-wheel and gearing at 42, secured thereto, turning a worm-screw, 43, which turns through a bracket, 44, rigid on the bracket-frame 40, in practically the same way as described in my previous application. The upper part of the frame 39 is guided in its vertical movements by the ways 120 45 45, rigid to the walls of the room. The frame 39 is provided with an interior panel or wall, 46, on which are suspended the swinging tables 47 and 48. These tables 47 and 48

are each provided at their rear edge with a fixed upright, 49, through and by which one table is suspended above the other, the pivotal points being in the same vertical line, by 5 bolts 50 50, passing through the uprights 49 49 and through the wall 46, on which bolts the tables 47 and 48, respectively, have corresponding lateral oscillation. These tables 47 and 48 are each secured against vibration 10 with reference to its upright by means of the brace-bars 51 51, which brace-bars are made rigid at their respective ends to the table and to the upright.

The wall 46 is preferably constructed in 15 sections, the surfaces of which are in different planes, as shown in Figs. 8 and 9, the division-line between which sections is at the step or shoulder 52 52, and the tables 47 and 48 are each suspended on and against a separate section, whereby the upright and braces 20 of the table 48, being on a deeper or inner section, are carried under or behind the table 47, thus providing for the proper location and oscillation of the tables with reference to their 25 arcs and required nearness to each other.

The extent of the oscillation of the tables 47 and 48 is limited by the walls or shoulders 52 and 53. These tables 47 and 48, in their rear edges, are each provided with a series of 30 apertures, 54, which series of apertures in location and distance apart correspond exactly with each other. Corresponding pins, 55 55, supported and movable endwise in bushings 56 56 in the wall 46, are adapted to enter the 35 apertures 54, whereby the tables may be adjusted either to the right or left and held in corresponding position by the pins 55 being inserted in corresponding apertures in the two tables. The inner or concave surfaces of 40 these two tables have the same arc, and the upper one is adapted to hold the pattern and the lower one the material for being carved, and are for use when carving is to be produced on curved material—such as the top 45 cross-bar of bent-back chairs. To secure the pattern and the material to be carved upon the tables, several series of apertures, 57 57, are made through the tables, through which are inserted sets of iron clamps 58 58, provided with hand-nuts 59, turning on the screw-threaded shanks thereof and bearing on the outside against the outer surface of the tables.

It will be understood that the upper table, 55 47, is located and adapted for holding the pattern against which the guide 29 is adapted to bear, and that the table 48 is located and adapted to receive the material to be cut by the tool 32. A shifting-rod, 60, supported and 60 having vertical movement in brackets on the post A, and provided with a finger, 61, is adapted by means of the lever 62, pivoted on frame 40, to shift the belt K back and forth on the fixed and loose pulleys H and I.

65 A slot, 66, is provided in the upright 49 of the table 48, through which the pin 55 passes that enters the upper table, 47, which slot is

constructed to permit of the required oscillation of the table 48.

What I claim as new, and desire to secure 70 by Letters Patent, is—

1. In a carving-machine, a swinging arm, 2, pivoted at two points at a distance apart in the same vertical line, in combination with two hinges, 3 and 4, to one of which hinges the 75 arm is secured by set-screws passing through curved slots in the arm and turning into the hinge, permitting slight oscillation about the horizontal axis of the arm, and to the other of which hinges the arm is secured by set-screws passing through curved laterally-extending slots and turning into the hinge, whereby short segmental motion and adjustment are provided for, substantially as described. 80

2. In a carving-machine, a swinging standard, 8, in combination with a tool and guide carrying frame supported and having vertical movement on the standard, such frame being provided with two sets of bearings, 19 19 and 19' 19', and the standard 8 being provided with two sets of corresponding ways, in which the bearings 19 19 and 19' 19' are adapted to travel, substantially as and for the purpose described. 95

3. In a carving-machine, a pair of curved tables for holding the pattern and material to be carved, respectively, suspended one above the other and oscillating laterally in the same or parallel vertical planes in arcs 100 parallel with each other, in combination with a vertically or nearly vertically moving cutting-tool and guide-carrying frame, substantially as described.

4. In a carving-machine, a pair of curved 105 tables for supporting the pattern and the material to be carved, respectively, suspended one above the other and adapted to swing in parallel arcs, and provided with corresponding apertures, 54 54, in combination with a 110 supporting-wall, 46, and retaining-pins 55 55, substantially as described.

5. In a carving-machine, a material-holding table having a concave surface on which the material rests, which table is so suspended as 115 to swing in the arc of its curved surface, and which table is provided with a series of apertures, 57 57, and with clamps 58 58, substantially as described.

6. In a carving-machine, a vertically-moving 120 frame, 39, and a wall or panel, 46, therein, the surface of which panel is in sections in different planes separated by steps or shoulders, in combination with oscillating tables, each of which tables is suspended on an individual 125 and distinct section and plane of the panel, substantially as described.

In testimony whereof I affix my signature in presence of two witnesses.

STEPHEN F. MOORE.
